UNITED STATES PATENT OFFICE.

FRANK ACKERMANN, MORRIS LANGHAUS, AND HERMAN GOULD, OF NEW YORK,
N. Y.; SAID LANGHAUS ASSIGNOR TO SAID ACKERMANN AND SAID GOULD.

MACHINE FOR MAKING AND DISPENSING LATHER.

Application filed August 29, 1924. Serial No. 734,855.

To all whom it may concern:

Be it known that we, FRANK ACKERMANN, MORRIS LANGHAUS, and HERMAN GOULD, citizens of the United States of America, residing at New York city, Bronx County, State of New York, have invented certain new and useful Improvements in Machines for Making and Dispensing Lather, of which the following is a specification.

10 This invention relates to machines for making and dispensing lather and in particular to a type adapted to be used in barber shops for producing at desired periods sufficient quantities of lather for shaving purposes.

20 A particular object of the invention is to produce a machine which will mix a certain quantity of water and soap powder to produce a lather, and from which the lather produced may be drawn at will.

25 A further object of the invention is to produce a machine in which the mixing of the soap powder and water may be regulated and in which the desired thickness of lather may be regulated.

30 A further object of the invention is to provide in a machine of this character, means whereby the making of the lather will be entirely automatic, that is, when a 35 fresh quantity of lather is needed a lever will be operated which will cause the mixing of the powder with a predetermined amount of water and the starting of an agitator which will produce the lather, and also a means for timing the movement of the agitator and automatically stopping it when the lather reaches the desired consistency.

40 A further object of the invention is to produce a machine in which the lather made will remain in its wet consistent state for long periods of time, so that one mixture of the lather may be sufficient for a number of shaves, it being understood, of course, that one machine may serve several barbers.

45 Referring to the drawings wherein we have shown a preferred embodiment of our invention,

Figure 1 is a top plan view of a machine constructed in accordance with our inven-

tion. The top cover of the machine being 50 removed to disclose the interior parts thereof,

Figure 2 is a side elevation in section taken on the line 2—2 of Figure 1, the soap powder hopper and agitator or mixing 55 chamber being shown in cross section.

Figure 3 is a side elevation taken on the line 3—3 of Figure 1, some of the parts being shown in section.

Figure 4 is a fragmentary side elevation 60 of one corner of the machine wherein is disposed the timing device which regulates the movement of the agitator and controls the general operation of the machine.

Figure 5 is a section taken through the 65 timing pump to show the interior construction of the same and;

Figure 6 is a side elevation of a portion 70 of the mixing tank showing the nozzle from which the prepared lather is discharged.

Referring to the drawings in detail 5 indicates a base which may be of wood or other suitable material upon which is mounted the cover or housing 6, which may be made of polished metal or other suitable 75 material.

Within the housing and attached thereto we provide a frame 7 in which is supported a water tank 8, having disposed across the top thereof a suitable cross bar 9 which carries an upwardly extending sleeve 10, in the upper end of which is pivoted a water releasing cam arm 11, the end of which within the sleeve 10 is provided with an extended portion 12, which engages the upper end of a 80 valve stem 13; the valve stem being retained in raised position by a suitable spring 14 which surrounds said stem and presses upwardly against the collar 15. The lower end of the valve stem is provided with a 85 valve 16 which is adapted to seat in a suitable opening 17 in the bottom of the water tank. This opening provides an inlet from the main water tank 8 into an auxiliary water tank 18 which is suitably fastened 90 against the bottom of the water tank 8. The auxiliary water tank 18 is open to atmosphere through the medium of a pipe 19,

95

which extends above the top of the water tank 8.

We may provide in the water tank 8 a suitable electric heater 20 made up of the usual resistance coil 21, which is electrically connected to the prongs 22 fastened in the wall 6 of the housing.

The auxiliary water tank 18 is provided in its bottom with an opening 23 against which is adapted to seat valve 24, which is normally retained in the closed position by the coil spring 25, which bears against a cross bar 26 disposed in the auxiliary tank outlet 27, the latter being connected to the mixing tank inlet 28 through the medium of an elbow 29. The valve 24 is, of course, provided with the usual valve stem which passes through the cross bar 26, and has its upper end extending into the auxiliary water tank 18 in position to be engaged by the lower end of the valve stem 13 when the water releasing cam arm 11 is operated.

It will be apparent that any pivoting of the cam arm 11 at its pivot point will cause a downward movement of the valve stem 13, which will cause the valve 16 to seat on the bottom of the water tank and will cause the valve 24 to open, thus allowing water in the auxiliary tank 18 to run into the agitator chamber 30, and at the same time, closing the opening 17 between the main water tank 8 and said auxiliary tank. Thus the water in the auxiliary tank is sufficient for one mixing with a certain quantity of soap powder and when the arm 11 is released the valve 24 closes the bottom of the auxiliary tank and allows valve 16 to open whereby the auxiliary tank is again refilled. In order to regulate the amount of water that may be required, we provide an extension 31 on the valve stem 13, said extension passing through the top of the housing 6 and carrying at its upper end a suitable knob 32 so that the valve stem 13 may be operated independently of the automatically operated lever 11.

The housing is provided with a screw cap 33 in the top thereof immediately over the main water tank 8 so that the tank can be filled with a supply of water.

The cam arm 11 is connected through the medium of a rod 34 to the operating lever 35 which is disposed at one side of the machine and is pivoted to a standard 36 supported on the side wall of the housing 6, the free end of said operating lever 35 being normally held in raised position by a coil spring 37. The free end of the lever 35 is adapted to be engaged by a hook 38 carried on the upper end of the timing pump piston rod 39, the lower end of said piston rod being disposed within pump chamber 40 and carrying the piston 41 which makes contact with the inner wall of said chamber. This piston rod 39 as shown in Figure 5 is hollow

in its lower end and is adapted to receive the end of a guide pin 42 around which is wound the spiral spring 43, the end of the spring abutting against the bottom of the recess in the piston rod 39. The rod 42 extends into the piston rod a sufficient distance to guide same in its downward movement, and in order to further guide the piston 39 we provide a bracket 44 suitably attached to the side wall of the housing 6.

The piston rod is provided in its hollow portion with a threaded opening 45 which receives loosely a screw 46 under the head of which is disposed a soft leather washer 47, it being apparent that this opening is used as an air inlet and when the air is exhausted in the lower end of the pump it will slowly seep in through said opening and assist the spring 43 to gradually force the piston upwardly. The time necessary for the air to enter is regulated by the screw 46, as when it is tightened up the washer 47 will prevent the rapid entrance of air and allow the piston to rise slowly so that any adjustment in time necessary for the piston to rise is provided by manipulating the screw 46.

The piston rod 39 is provided with an extension 48 which passes through a suitable slot 49 in the side wall of the housing 6 and carries at its outer end a knob 50^A which, as shown in Figure 4, is depressed to cause a downward movement of the piston 41 in the timing pump 40. The downward movement of the piston 39 will cause the hook 38 to draw down the operating lever 35 and when said operating lever is at its lower most position, it will be engaged by a free moving pivoted hook 50, and will be thus retained in its lower position. A suitable dowel pin 51 on the piston 39 normally holds the hook in disengaged position relatively to the lever 35 when the piston rod is raised, so that when the piston rod is pushed down, the lever 35 will pass under the hook and be retained thereunder until the air escapes from the timing pump and allows said piston rod 39 to rise so that its dowel 51 engages the extended portion 52 of the hook to release the lever 35.

This operation of the lever 35 causes, as before stated, the regulation of the water through the medium of the rod 34 and lever 11.

The arm 35 has attached thereto in any suitable manner a curved cam 53 which extends inwardly adjacent the free end of the lever 35 to engage a roller 54 carried between the extended arms 55 of the powder plunger 56 which operates in a casing 57 to move the powder from beneath a suitable hopper 58 to the mixing cup or agitator chamber 30. The casing 57 is provided with a hopper receiving portion 59 into which is fitted the lower part of an outer hopper 58, which is

beaded at its upper end as at 60 to support an inner hopper 61, the inner hopper being the one which carries the soap powder as shown in Figure 2. The inner hopper is provided 5 with oppositely disposed pin members 62 adjacent its lower end, the pins extending through the outer hopper 58 to be engaged by the arms 63. The lower ends of the arms 63 are pivoted to the opposite sides of the 10 powder plunger 56, the connecting pins passing through suitable slots 64 in the casing 57. Any movement of the powder plunger 56 will, of course, cause the agitation of the inner hopper 61 to loosen the powder which has a 15 tendency to become caked. The end of the casing is projected to provide arms 65, which carry at their outer ends pins 66 to which is attached coil spring 67. The inner ends of the springs engage pins 68 20 which are fastened to the powder plunger 56 and operate in the slots 64.

It is apparent, therefore, that upon a downward movement of the free end of the lever 35 the cam 53 will turn against the 25 roller 54 and cause the inward movement of the powder plunger 56, which will move the powder out of the bore 69 in the frame 57 into the mixing cup 30. At the same time that the arm 35 is moving downwardly the 30 water will be released and it too will pass into the mixing cup, together with the powder. In order that the powder may be regulated independently one of the pins 68 is projected through the wall of the casing 35 35 65 through a suitable slot and carries at its outer end a knob 70, which may be moved back and forth to operate the powder plunger, independently of the cam 53. The movement of the powder plunger 56 may 40 be regulated by providing a slidale stop 71 in the slot through which the plunger operator works, it being readily seen that when the stop 71 is advanced, the powder plunger will be limited in its return movement 45 and thus the amount of powder that will be projected into the mixing chamber will be regulated.

The mixing chamber is held on the top of a suitable standard 70^A, under which is 50 placed a motor 71^A. The motor shaft extending up through the standard 70^A and the bottom of the mixing tank 30 and carrying at its upper end the agitator hub 72, said hub being provided with blades 73, which 55 churn up the mixture of powder and water to form a lather. The mixing chamber is properly insulated so that no water can find its way from the mixing chamber into the interior of the motor. The chamber 30 is 60 provided adjacent its lower end with a discharge nozzle 74 (see Figure 6), the nozzle being bent so that the lather will not run out. In order to force the lather out use is made 65 of a piston 75 which fits closely within the chamber 30 and is carried on the lower end

of an operating rod 76, the upper end of which passes through the top of the housing 5 and is provided with a suitable knob 77, which when pressed downwardly causes the piston 75 to move down and the lather 70 to be discharged through the nozzle 74.

The water tank is provided with a suitable gage 77^A. In order to start the motor at the proper time, we provide the contact 78 which is yieldably carried on the guide screw 79, 75 which is held in a suitable fibre block 80 carried on the end of a bracket 81, the latter being attached to the side wall of the housing 6.

The operating lever 35 is provided with a suitable pin 82, which engages the contact plate 78 when the lever reaches the limit of its downward movement. The screw 83 which helps carry the plate 78 is connected to the motor through the medium of a wire 84 as is the pin 82 on the arm 35 by the wire 85. Thus, when the lever is at its downward limit the motor begins its operation, this operation beginning after the soap powder and water have been put into the chamber 30. 90

When the air has escaped from the timing pump 40, the hook will release the lever 35 and allow it to return to its normally raised position thereby breaking the motor circuit and allowing the auxiliary tank 18 to be 95 filled with water, thus completing the cycle of operations necessary in the production of lather.

It will be seen, therefore, that we have provided a machine which will automatically feed a combination of soap powder and water to a mixing chamber where the same will be agitated until a lather of a desirable consistency is produced. When the lather is completed the machine will automatically 100 stop and the mixing tank forming a part thereof being more or less air tight, will preserve the lather without letting the same dry up. 105

We desire it understood that, although we have shown and described a preferred embodiment of our invention, various details thereof may be varied, and the principle of our invention embodied in other forms, without departing from the general scope of the 110 invention. 115

Having now described our invention what we claim and desire to secure by Letters Patent is:

1. In combination with a lather making 120 machine, a powder hopper, a mixing chamber, and means for feeding the powder from the hopper to the mixing chamber, said means also causing agitation of said hopper.

2. In combination with a lather making 125 machine, a powder container, a source of water supply, a mixing chamber, an agitator journaled in the bottom of said chamber, a motor for driving said agitator, and means for feeding the powder and water to said 130

chamber, said means being adapted to close the circuit to start the motor for driving the agitator.

3. In combination with a lather making machine, a main water tank, an auxiliary water tank, an outlet from the main tank to the auxiliary tank, an outlet from the auxiliary tank, and means for automatically closing one outlet when the other is opened.

10 4. In a lather mixing machine, a water tank, a powder hopper, a mixing chamber, means for automatically feeding the powder and water to the mixing chamber and means for discharging the mixture from the mixing chamber in any desired quantity.

5. In a lather mixing machine, a water tank, a powder hopper, a mixing chamber, means for automatically feeding the powder and water to the mixing chamber simultaneously, an agitator in said chamber, and a timing member for regulating the duration of the mixing operation.

6. In combination with a lather mixing machine, a mixing chamber, means for feeding thereto material to be mixed, and a timing device for regulating the duration of the mixing operation.

7. In combination with a lather mixing machine, a mixing chamber, means for feeding thereto material to be mixed, a timing device for regulating the duration of the mixing operation, and means for setting the timing device so that it will operate in a given period of time.

35 8. In combination with a lather mixing machine, a mixing chamber, means for feeding thereto material to be mixed an agitator in said chamber and a piston in said chamber for discharging the mixture in any desired quantity.

40 9. In a lather mixing machine, a main water tank, an auxiliary tank associated

therewith, a plurality of valves for said tanks one of which operates the other, means for automatically moving the operating valve, and means whereby said operating valve may be moved independently of said automatic means.

10. In a lather mixing machine, a mixing tank, means for feeding thereto materials to be mixed, an operating lever, a time pump adapted to engage said lever to draw the same down and start the operation of the machine, means for holding said lever down while the pump is returning to its extended position, and means for releasing the lever to stop the operation of the machine when the pump has returned to its extended position.

11. In a lather mixing machine, a mixing tank, a powder hopper, a plunger operable beneath said hopper to feed powder to the tank, means for automatically operating said plunger, and a hand operated lever for operating said plunger independently of the automatic operating means.

12. In a lather mixing machine, a powder hopper, a water supply, a mixing chamber, means for feeding the water and powder to said chamber, means for shaking said hopper to loosen the powder, an agitator in the mixing chamber, means for automatically starting the agitator when the water and powder are fed to the chamber, a timing device for automatically stopping said agitator after a lapse of time, and means in said mixing chamber for discharging the prepared lather.

In testimony whereof we hereunto affix our signatures.

FRANK ACKERMANN.
MORRIS LANGHAUS.
HERMAN GOULD.
